Primary Examiner — Lakiya G Rogers*Assistant Examiner* — Altaira J Swangin(74) Attorney, Agent, or Firm — Schwabe Williamson & Wyatt, P.C.(57) CLAIM

We claim the ornamental design for a headlamp, as shown and described.

DESCRIPTION

FIG. 1 is a perspective view of a headlamp, showing our new design;

FIG. 2 is a front view thereof;

FIG. 3 is a back view thereof;

FIG. 4 is a right view thereof;

FIG. 5 is a left view thereof;

FIG. 6 is a top view thereof; and,

FIG. 7 is a bottom view thereof.

The dashed lines are included for illustrating unclaimed portions of the article, and form no part of the claimed design.

1 Claim, 5 Drawing Sheets(56)
